UNITED STATES PATENT OFFICE.

DELOS ALLEN, OF LOS ANGELES, CALIFORNIA, ASSIGNOR TO THE ANTIFRICTION JOURNAL BOX COMPANY, OF LOS ANGELES, CALIFORNIA, A CORPORATION OF CALIFORNIA.

ANTIFRICTION JOURNAL-BOX.

No. 836,428.

Specification of Letters Patent.

Patented Nov. 20, 1906.

Application filed June 21, 1904. Serial No. 213,450.

To all whom it may concern:

Be it known that I, DELOS ALLEN, a citizen of the United States, residing at Los Angeles, in the county of Los Angeles and State of California, have invented new and useful Improvements in Antifriction Journal-Boxes, of which the following is a specification.

This invention relates to improvements on the type of antifriction journal-bearing disclosed in my application filed February 18, 1904, Serial No. 194,123, comprising a plurality of antifriction-rollers arranged between the axle and the cylindrical bearing, with separating-rollers between said antifriction-rollers and collars at each end of the box upon which these separating-rollers travel, means being provided for retaining these separating-rollers in contact with said collars.

The primary object of the present invention is to provide a roller-bearing especially adapted for heavy work, and particularly where heavy end thrust or strain is to be withstood.

A further object of the invention is to facilitate the assembling of the parts of the box and to enable the interior parts thereof to be quickly removed for cleaning or oiling.

The accompanying drawings illustrate the invention.

Figure 1 is a longitudinal section of the box, showing the internal sleeve in elevation and the antifriction-rollers in the vertical plane. Fig. 2 is a transverse section on the line $x^2 x^2$ in Fig. 1. Fig. 3 is a transverse section on the line $x^3 x^3$ in Fig. 1. Fig. 4 is a detail section of one of the outer cylindrical members. Fig. 5 is a view similar to Fig. 1 with the sleeve in section and the separating-rollers in a vertical plane. Fig. 6 is a detail elevation of the sleeve. Fig. 7 is a detail elevation of an antifriction-roller. Fig. 8 is a detail elevation of a spacing-roller. Fig. 9 is a detail elevation of a retaining and guide collar for the spacing-rollers.

It will be understood that the invention is applicable in connection either with journal-boxes for rotating shafts or with rotating boxes or hubs for non-rotary axles; but the construction herein shown has certain special advantages in connection with heavy work, such as car-truck bearings or heavy bearings.

in general where the end thrust is considerable.

In the drawings the invention is illustrated as applied to an axle and to the wheel-hub or bearing rotating thereon. 1 designates such hub, or generally the outer cylindrical member of a journal-box, and 2 designates the axle, or generally the inner journal member or shaft. The member 1 is formed as a cylinder or tubular shell provided with internal cylinder members 11, which are rigidly but removably secured to member 1, as by means of screws 21 extending inwardly from the periphery of said member 1, and constitute the actual outer bearing means. Said cylinders 11 are separated from one another sufficiently to leave an annular channel or groove 31 between the inner ends thereof. After the inner set of screws 21 are loosened and the outer cap 14 removed, the outermost of the cylinders 11 may be removed, together with hub 1, thereby exposing the outer half of rollers 6 and 7. When this has been done, oil may be injected back of and between ribs 16, so that the portion of the bearing still inclosed by innermost sleeve 11, as well as the exposed portion thereof, may be lubricated. A sleeve 3 fits on said axle or journal member and is connected therewith so that it cannot rotate relatively thereto—for example, by means of a projection, as a pin or key 4 on the axle engaging in a notch 5 in said sleeve. The sleeve 3 constitutes the inner bearing member of the journal-box. The notch 5 and pin 4 being at the inner end of the axle-bearing, the sleeve is detachable from the axle, as hereinafter set forth.

A series of antifriction-rollers 6 are arranged between the inner and outer bearing members 11 3, these rollers being of a size to contact simultaneously with both the inner and outer members and form an antifriction roller-bearing between them. A series of 95 separating-rollers 7 are arranged between successive rollers 6, so as to roll in contact with said rollers 6 and prevent contact of the latter with each other. The internal sleeve or bearing member 3 has an annular groove 100 or channel 13 in the plane of the annular channel 31, and the rolls 6 are each provided with an annular rib 16, engaging in said groove 13 and also in the channel 31, so as to

hold the inner and outer bearing members firmly against end thrust and endwise longitudinal displacement.

At the respective ends of sleeve 3 are provided collars 8, provided with annular flanges or tracks 18, upon which roll reduced portions or necks 17 of the respective rollers 7, and annular grooves 28 to receive the heads or flanges 27 at the ends of said rollers. 5 These collars are attached to and supported by caps 14, which are interiorly screw-threaded to engage over corresponding screw-threaded ends of the hub or outer shell 1, the collars being secured to the respective caps 14 by screws passing through holes in said caps and screwing into said collars. The caps 14 have central openings which fit over the corresponding portions of the central shaft or journal 2, and thereby 15 center the collars 8 and the series of separating-rollers 7. Rings 20 are provided at the ends of these rollers, said rings surrounding the entire series of rollers and engaging with the reduced portions 17 thereof to hold the 20 same in rolling contact with the flanged portions 18 of the collars 8.

At each end of the box I prefer to provide dust-proof end bearings, which may consist of gaskets or washers 26, of fiber or other suitable material, supported by end caps 15, which are recessed to contain said washers. 30 Each of the caps 14 may be recessed to receive a dust-proof packing or felt washer 30, against which the end bearing-washer 26 bears. The central axle-shaft or journal 2 may have a collar or flange 12 and a screw portion 32, receiving a nut 33, the box as a whole being held between the said flange 12 and nut 33, the outer face of one end cap 15 35 bearing against the flange 12 and the outer face of the other end cap 15 bearing against the nut 33.

34 designates a jam-nut for the nut 33.

It is desirable to prevent rotation of the 45 inner end cap 15, and to this end it may be provided with a notch 35, engaging with a projection, as a pin 36, on the axle member 2.

When the journal-box is in use, the cylinder members 11 engage with the flange or 50 ribs 16 of the antifriction-rollers, which in turn engage with the groove 13 in the sleeve 3 to hold the members 1 and 3 against relative endwise displacement. Hardened-steel washers 38 may be provided at the inner 55 ends of cylinder members 11 to take the wear and end thrust.

It will be seen that when the nuts 34 and 33 are unscrewed and the cap 14 at the outer end of the journal (shown in Fig. 1) is removed it will only be necessary to loosen screws 21 in order to remove the inner cylinders 11, rollers 6 and 7, and sleeve 3 when it is desired to clean or oil these parts.

What I claim is—

65 1. The combination of a central journal

and a sleeve detachably mounted thereon, means for preventing relative rotation of said sleeve and journal, a collar at each end of the sleeve and engaging the sleeve, an outer bearing member comprising a cylindrical shell, 70 and two inner cylinders detachably secured to the shell and separated to form an annular channel, washers at the inner ends of said inner cylinders, a series of antifriction-rollers around said sleeve, each having an annular rib to engage in said channel, said sleeve being provided with an annular groove to receive and engage said annular ribs to prevent longitudinal movement of the sleeve and rollers and outer bearing member, separating- 75 rollers arranged between said antifriction-rollers, each separating-roller having a neck at each end and an annular groove to receive the ribs on the antifriction-rollers, rings around the separating-rollers for engaging 80 said necks, a cap at each end of the outer bearing member, detachably secured to said outer bearing member and means accessible from the outside of the caps, detachably securing said caps to said collars. 90

2. The combination of a central journal and a sleeve detachably mounted thereon, said sleeve and journal being provided with means for preventing relative rotation, a collar at each end of the sleeve and engaging the 95 sleeve, an outer bearing member comprising a cylindrical shell and two inner cylinders detachably secured to the shell and separated to form an annular channel, both said cylinders being removable in the same direction 100 when detached, a series of antifriction-rollers around said sleeve each having an annular rib to engage in said channel, said sleeve being provided with an annular groove to receive and engage said annular ribs to prevent 105 longitudinal movement of the sleeve and rollers and outer bearing member, separating-rollers arranged between said antifriction-rollers, each separating-roller having an annular neck at each end for bearing on said 110 collars, and an annular groove to receive the ribs on the antifriction-rollers, rings around the separating-rollers for engaging said necks, a cap at each end of the outer bearing member, detachably secured to said outer bearing 115 member and means accessible from the outside of the caps detachably securing said caps to said collars.

3. The combination with a central journal member and a sleeve member, one of said members being provided with a pin and the other with a notch for engaging said pin for detachably connecting and preventing relative rotation of said members, a collar at each end of the sleeve and engaging the sleeve, 120 an outer bearing member comprising a cylindrical shell and two inner cylinders detachably secured to the shell and separated to form an annular channel, a series of antifriction-rollers around said sleeve each having 125

- an annular rib to engage in said groove, said sleeve being provided with an annular groove to receive and engage said annular ribs to prevent relative longitudinal movement of the sleeve and rollers and outer bearing member, separating-rollers arranged between said antifriction-rollers, each separating-roller having an annular neck at each end for bearing on said collars, and an annular groove to receive the ribs on the antifriction-rollers, rings around the separating-rollers for engaging said necks, and a cap at each end of the outer bearing member, detachably secured to said outer bearing member and means accessible from the outside of the caps detachably securing said caps to said collars.
4. The combination of a central journal and a sleeve detachably mounted thereon, said sleeve and journal being provided with means for preventing relative rotation, a collar at each end of the sleeve and engaging the sleeve, an outer bearing member comprising a cylindrical shell and two inner cylinders detachably secured to the shell and separated to form an annular channel, a series of antifriction-rollers around said sleeve each having an annular rib to engage in said channel, said sleeve being provided with an annular groove to receive and engage said annular ribs to prevent relative longitudinal movement of the sleeve and rollers and outer bearing member, separating-rollers arranged between said antifriction-rollers, each separating-roller having an annular neck at each end for bearing on said collars, and an annular groove to receive the ribs on the antifriction-rollers, rings around the separating-rollers for engaging said necks, a cap at each end of the outer bearing member, detachably mounted thereon, a collar at each end of the sleeve and engaging the sleeve, an outer bearing member comprising a cylindrical shell and two inner cylinders detachably secured to the shell and separated to form an annular channel, a series of antifriction-rollers around said sleeve each having an annular rib to engage in said channel, separating-rollers between said antifriction-rollers, and a cap at each end of the outer bearing member for holding all the aforementioned rollers in place.
5. The combination of a central journal and a sleeve detachably mounted thereon, a collar at each end of the sleeve and engaging the sleeve, an outer bearing member comprising a cylindrical shell and two inner cylinders detachably secured to the shell by means accessible from the outer periphery thereof and separated to form an annular channel, a series of antifriction-rollers around said sleeve each having an annular rib to engage said channel, separating-rollers between said antifriction-rollers, and a cap at each end of the outer bearing member for holding all the aforementioned rollers in place.
6. The combination of a central journal and a sleeve detachably mounted thereon, a collar at each end of the sleeve and engaging the sleeve, an outer bearing member comprising a cylindrical shell and two inner cylinders detachably secured to the shell and separated to form an annular channel, a series of antifriction-rollers around said sleeve each having an annular rib to engage said channel, separating-rollers between said antifriction-rollers, and a cap at each end of the outer bearing member for holding all the aforementioned rollers in place.

In testimony whereof I have hereunto set my hand, at Los Angeles, California, this 14th day of June, 1904.

DELOS ALLEN.

In presence of—

ARTHUR P. KNIGHT,
JULIA TOWNSEND.
